UNITED STATES PATENT OFFICE.

FREDERICK S. PINKUS, OF NEW YORK, N. Y.

DESIGN FOR A TABLE-CLOTH.

SPECIFICATION forming part of Design No. 21,928, dated October 25, 1892.

Application filed September 19, 1892. Serial No. 446,337. Term of patent 7 years.

To all whom it may concern:

Be it known that I, FREDERICK S. PINKUS, a citizen of the United States, residing at New York, in the county of New York, State of New York, have invented and produced a new and original Design for Table-Cloths, of which the following is a specification, reference being had to the accompanying drawing, showing a part thereof.

My design consists of a table-cloth having its corners truncated and with a continuous fringe carried around all the sides and truncated corners, continuous with interior lines of "drawn work" running parallel with the sides and truncated corners.

In the drawing, A represents the body of the table-cloth made according to my design. The truncated corners are shown at B. The

continuous fringe is shown at b, and the lines of drawn work or equivalent ornamental lines are shown at d. Some of these follow the truncated edges and are parallel therewith.

I have shown the table-cloth provided with but a quadrant of the pattern. The remaining quadrants, being identical therewith, are omitted as not being necessary to the illustration of my design.

I claim—

A design for a table-cloth, substantially as shown and described.

In testimony whereof I affix my signature in presence of two witnesses.

FREDERICK S. PINKUS.

Witnesses:

WM. LOW,
THOMAS J. BAKER.
